UNITED STATES PATENT OFFICE.

DAVID CHRISTOPHER BLACK, OF NEWCASTLE-UPON-TYNE, ENGLAND, ASSIGNOR TO THE PARSONS MARINE STEAM TURBINE COMPANY LIMITED, OF WALLSEND, ENGLAND.

SHIP-PROPULSION INSTALLATION.

1,336,018.

Specification of Letters Patent.

Patented Apr. 6, 1920.

Original application filed January 19, 1918, Serial No. 212,746. Divided and this application filed November 21, 1919. Serial No. 339,664.

To all whom it may concern:

Be it known that I, DAVID CHRISTOPHER BLACK, a subject of the King of Great Britain and Ireland, and residing at 88 Park road, Newcastle-upon-Tyne, in the county of Northumberland, England, have invented certain new and useful Improvements in and Relating to Ship-Propulsion Installations, of which the following is a specification.

10 The present invention relates to ship propulsion installations of the type where two or more motors or sets of motors drive through gearing, two or more propeller shafts, and particularly of the type described 15 in United States application No. 212746 of which this case is a division.

The object of the invention is to arrange the engines, intermediate shafts and gearing in such a manner as to give the maximum 20 hold space in the vessel and to minimize the hold space occupied by the power transmission system.

The invention consists in a marine propulsion installation in which a plurality of 25 propeller shafts are employed connected with driving means by intermediate shafts which are geared both to the propeller shafts and to the driving means, the intermediate shafts being displaced axially out of line with the 30 propeller shafts and nearer the sides of the ship than the propeller shafts so that a greater hold space is provided.

Referring to the accompanying drawings:

35 Figure 1 is a plan of a two-shaft installation arranged according to the invention.

Fig. 2 is a plan of an installation in which additional propeller shafts are provided, while Fig. 3 is a plan of another modification 40 in which additional propeller shafts are employed.

In the form of the invention shown in Fig. 1, the intermediate shafts 1, 2, are placed in tunnels 3, 4, built against the sides 45 of the ship. The reduction gearings are divided, the first reductions 5, 6, being placed in the engine room in such a position that the intermediate shafting is well outside the main portion of the engines and gear- 50 ing. The second reductions 7, 8, are placed as far aft in the vessel as possible and are so arranged that the propeller shafting *a b* is considerably nearer the central line of the vessel than the intermediate shafting. 55 In this manner a very considerable width of

hold space is provided without any central tunnels for the shafting. The gears may be single or multiple.

In the form of the invention shown in Fig. 2, in addition to the propeller shafting *a b*, and intermediate shafts 1, 2, additional propeller shafts *c d* and intermediate shafts 11, 12, are provided, the intermediate shafts being geared at one end of a propeller shaft and at the other end to the engines. 60

In the form of the invention shown in Fig. 3, the additional propeller shafts *c' d'* are passed along tunnels near the sides of the ship and are geared to the engines by 65 gearing 15, 16.

Having now described my invention, what I claim as new and desire to secure by Letters Patent is:—

1. In marine propeller installations a plurality of propeller shafts, driving means in 75 an engine room, shafts intermediate the driving means and the propeller shafts and extending along the hull of the vessel aft of the engine room, each of said intermediate shafts being disposed axially out of line with 80 the propeller shaft it is to drive, tunnel means in which said shafts are located and gearing between each aft end of the intermediate shaft and its propeller shaft, said 85 gearing being spaced from the engine room aft the hold, said intermediate shafts being displaced toward the side of the ship from the propeller shafts, providing greater unbroken hold space.

2. In marine propeller installations a plurality of propeller shafts, driving means in 90 an engine room, shafts intermediate the driving means and the propeller shafts and extending along the hull of the vessel aft of the engine room, each of said intermediate 95 shafts being disposed axially out of line with the propeller shaft it is to drive, tunnel means in which said shafts are located and gearing between each aft end of the intermediate shaft and its propeller shaft, said 100 gearing being spaced from the engine room aft the hold, said intermediate shafts being displaced toward the side of the ship from the propeller shafts, providing greater unbroken hold space, said tunnels being placed 105 along the sides of the vessel, as set forth.

In testimony whereof I have signed my name to this specification.

DAVID CHRISTOPHER BLACK.
